(57) **CLAIM**

The ornamental design for a combined camera and microphone, as shown and described.

DESCRIPTION

FIG. 1 is a front, elevational view of a combined camera and microphone showing my new design;

FIG. 2 is a rear elevational view thereof;

FIG. 3 is a right side elevational view thereof, an undisclosed left side view being a mirror image thereof;

FIG. 4 is a top plan view thereof;

FIG. 5 is a bottom plan view thereof; and,

FIG. 6 is a perspective view thereof.

The portion of the camera in FIG. 2 shown in broken lines is for illustrative purposes only and forms no part of the claimed design.
